AUTOMATIC TRAIN CONTROL

Paul J. Simmen, Eden, N. Y., assignor, by mesne assignments, to The Union Switch & Signal Company, Swissvale, Pa., a corporation of Pennsylvania

Application June 14, 1928, Serial No. 285,449

10 Claims.

(Cl. 246—3)

This invention relates to railway train control systems, particularly those in which both the signals and the switches are controlled both automatically and manually, and more especially to such systems in which an indication and record is made at a central station of the movements of trains.

This invention relates to a system whereby an operator at a remote point such as at a dispatcher's office, interlocking tower or way station is enabled to throw switches along the line of a railway and at the same time display signals to the engineer of an approaching train to indicate which position the switches are in. This invention is an improvement on the invention shown in my co-pending application filed April 10, 1923, Serial No. 631,099 and which is now U. S. Letters Patent 1,971,950.

An object of the invention is to provide means for throwing switches at both ends of a double end siding and to operate a plurality of distinctive signals to the engineer of an approaching train, and indicate by these signals information useful to the engineer for the safe and uninterrupted movement of trains.

Other objects and advantages will appear as the description of the invention progresses and the novel features will be particularly pointed out in the appended claims.

In describing the invention in detail, reference is had to the accompanying drawings wherein I have illustrated a preferred physical embodiment of my invention and wherein like characters of reference designate corresponding parts throughout the several views and in which:

Figure 1 is a schematic representation of the apparatus and circuits in the dispatcher's office, interlocking tower or way station and along the track; Fig. 2 is a schematic representation of the apparatus and circuits on the locomotive or car by which, with certain cooperating parts of Fig. 1, signals are displayed on the locomotive or car.

Fig. 1 shows a main track consisting of track rails 1 and 2. Rail 1 is electrically continuous and rail 2 is divided into sections by means of insulating joints as 3, thus dividing the track into block sections as A, B, C, D. Near one end of each block is a track battery as 4 and near the other end of each block are track relays as 5a, 5b, 5c and 5d, constituting with their connections to the rails, a track circuit well known to those skilled in the art. In blocks B and C a siding is shown as 6, having at its ends track switches as 7 and 8. At the clearance points of the siding, insulating joints as 3 electrically sepa-

rate the straight portion of the siding from the main track. At the switch points of the switches 7 and 8 are located power switch machines as 9 and 10. The switch machines 9 and 10 may be of any type well known to those skilled in the art, which includes a motor, which when current is supplied to it flowing in a certain direction, the switch machine will close the switch and if current is supplied flowing in the opposite direction, the motor will operate in the opposite direction and the switch machine will open the switch, that is, any type of power operated switch machine may be used which depends upon an electrical change to cause it to operate.

For the purpose of brevity in this specification by a "closed switch" is meant that a train moving from block A to block B, will continue on the main track; and by an "open switch" is meant, that the switch is in a position such that when a train is moving from block A to block B, it will proceed into a siding.

Along the track are located train control rails as 11 and 12, and 13 and 14. Train control rails 11 and 12 are for east bound train movements and train control rails 13 and 14 are for west bound train movements. Train control rails 11 and 13 are home train control rails and located near the entrance to a new block and train control rails 12 and 14 are distant train control rails, located approximately braking distance from the entrance to a new block.

In Fig. 1 are shown a polarized relay as 15 and an alternating current relay as 16 which are located along the track near switch 7 and suitably housed. Similar relays 115 and 116 are located near switch 8. In the dispatcher's office are two manually operable switches as 17 and 18. By the several positions of the switches 17 and 18, different electrical conditions can be created in relays 15 and 16 and 115 and 116 through circuits 35 to be described hereinafter, thus placing the armatures of these relays in several different positions and depending upon the position of these armatures, six different electrical conditions can be established in the train control rails. The circuits established by the armatures of relays 15 and 16 at switch 7, govern train control rails 11 and 12; and the circuits established by the armatures of relays 115 and 116 at switch 8, govern the train control rails 13 and 14.

Relays 15 and 16 and 115 and 116 are electrically controlled by the two manually operable switches 17 and 18 as hereinbefore stated. When switch 17 is in the right hand position, thus contacting with spring contact as 19, an electrical

connection is made to direct current source as 22. When switch 17 is in the left hand position, thus connecting with spring contact 20, an electrical connection is made with direct current source 23. 5 When switch 18 is in contact with spring contact 21, an electrical connection is made with alternating current source 24. Electrical sources 22, 23 and 24 are preferably located in the dispatcher's office. 10 Depending upon the several positions of switches 17 and 18, relays 15 and 16 at track switches 7 and 8 may be energized or deenergized through three different circuits, to wit: The positive direct current circuit; the negative direct current circuit; and the alternating current circuit.

The positive direct current circuit through relay 15 at switch 7 is as follows: From positive pole of battery 22, wire 25, impedance coil 26, wire 27, spring contact 19, switch 17, wire 28, 20 relay 29, wire 31, impedance coil 32, wires 33, terminal 34, wire 35, resistance 36, wire 37, terminal 38, wire 39, terminal 40, wire 41, polarized relay 15, wire 42, impedance coil 43, and wire 44 to track rail 1 and thence through wires 45 25 and 46 to negative pole of battery 22. A similar circuit is also established through a branch circuit to polarized relay 115 at switch 8 as follows: From terminal 34, wire 47, terminal 48, wire 49, resistance 50, wire 51, terminal 52, 30 wire 53, terminal 54, wire 55, polarized relay 115, wire 56, impedance coil 57, wire 58 to track rail 1 and thence the circuit is completed through battery 22 as hereinbefore described.

The negative direct current circuit through relay 15, at switch 7 is as follows: From positive pole of battery 23, wires 59 and 60 and 45, track rail 1, wire 44, impedance coil 43, wire 42, polarized relay 15, wire 41, terminal 40, wire 39, terminal 38, wire 37, resistance 36, wire 35, terminal 34, wire 33, impedance coil 32, wire 31, relay 29, wire 28, switch 17, spring contact 20, wire 61, impedance coil 62, wire 63, to negative pole of battery 23. A similar circuit is also established through a branch circuit to polarized relay at switch 8 as follows: From track rail 1, wire 58, impedance coil 57, wire 56, polarized relay 115, wire 55, terminal 54, wire 53, terminal 52, wire 51, resistance 50, wire 49, terminal 48, wire 47, to terminal 34 and thence the circuit 50 is completed through battery 23 as hereinbefore described.

The alternating current circuit through relay 16 at switch 7 is as follows: From alternating current source 24, wire 64, condenser 65, wire 66, 55 spring contact 21, switch 18, wire 67, alternating current relay 30, wire 68, condenser 69, wire 70, terminal 34, wire 35, resistance 36, wire 37, terminal 38, wire 71, alternating current relay 16, wire 72, condenser 73, wires 74 and 44, track rail 60 1 and wires 45, 60 and 75 to the alternating current source 24. A similar circuit is also established through a branch circuit to alternating current relay 116 at switch 8 as follows: From terminal 34, wire 47, terminal 48, wire 49, resistance 50, wire 51, terminal 52, wire 76, alternating current relay 116, wire 77, condenser 78, wires 79 and 58 to track rail 1 and thence the circuit is completed through alternating current source 24 as hereinbefore described.

70 Impedance coils 26, 62, 32, 43 and 57 are inserted to prevent the flow of alternating current through the circuits in which they are inserted and condensers 65, 69, 73, and 78 are inserted to prevent the flow of direct current through 75 the circuits in which they are inserted. Relays

29 and 30 in the dispatcher's office are for the purpose of indicating or recording train movements, which will be more fully described hereinafter. Resistances 36 and 50 are present in the circuits in which they are inserted to decrease the flow of current through relays 29 and 30, for the purpose to be explained hereinafter. 5

By means of the three hereinbefore described circuits, which will be referred to hereinafter, which are established through the several positions of the manually operable switches 17 and 18, six different electrical conditions can be established in relays 15 and 16 and 115 and 116, which result in the armatures of these relays assuming different positions and by reason of the 15 different positions of these armatures, different circuits are established to train control rails 11 and 12, and 13 and 14, so that the train control rails are charged with electrical energy in six different ways. 20

The six different electrical conditions of relays 15 and 16 and 115 and 116, and train control rails 11 and 12 and 13 and 14 are established as follows:

First condition.—When switch 17 is in contact with spring contact 19 and switch 18 is in contact with spring contact 21, polarized relays 15 and 115 are positively energized and alternating current relays 16 and 116 are also energized. Train control rails 11 and 12 and 13 and 14 30 are also energized with positive direct current and alternating current through certain branch circuits, which will be more fully described hereinafter. 25

Second condition.—When switch 17 is in contact with spring contacts 20 and switch 18 is in contact with spring contact 21, polarized relays 15 and 115 are negatively energized and alternating current relays 16 and 116 are also energized. Train control rails 11 and 12 and 13 and 14 are 40 also energized with negative direct current and alternating current. 35

Third condition.—When switch 17 is in contact with spring contact 19 and switch 18 is disconnected from spring contact 21, polarized relays 15 and 115 will be positively energized, but alternating current relays 16 and 116 will be deenergized and the train control rails will be energized with positive direct current only. 45

Fourth condition.—When switch 17 is in contact with spring contact 20, and switch 18 is disconnected from spring contact 21, polarized relays 15 and 115 will be negatively energized, but alternating current relays 16 and 116 will be deenergized and the train control rails will be 55 energized with negative direct current only. 50

Fifth condition.—When switch 17 is disconnected from both spring contacts 19 and 20, and switch 18 is in contact with spring contact 21, polarized relays 15 and 115 will be deenergized, 60 and alternating current relays 16 and 116 will be energized and the train control rails will be energized with alternating current only. 60

Sixth condition.—When switch 17 is disconnected from both spring contacts 19 and 20 and switch 18 is disconnected from spring contact 21, polarized relays 15 and 115 and alternating current relays 16 and 116 are deenergized and the train control rails are also deenergized. 65

I will now describe the branch circuits through 70 which the train control rails 11 and 12 are electrically conditioned in six different ways as hereinbefore outlined.

When polarized relay 15 is positively energized, alternating current relay 16 is energized with 75

alternating current, corresponding to the first condition, armatures 80, 81 and 82 of relay 15 will make contact with front contacts 83, 84 and 85 and polarized armatures 86, 87 and 88 will be 5 in the right hand position as shown in Fig. 1 and make contact with contact 89, 90 and 91. Armatures 92 and 93 of relay 16 will be in the energized position and armature 92 will make contact with front contact 94. This position of 10 the several armatures establishes a branch circuit from terminal 40 in the main dispatcher's circuit to train control rails 11 and 12 as follows: From terminal 40, wire 95, armature 92, front contact 94, wire 96, armature 80, front contact 15 83, wire 97, polarized armature 86, contact 89, wire 98, front contact 99, armature 100, of track relay 5b, wire 101, wires 102 and 103, to train control rails 11 and 12. It will thus be seen that when switches 17 and 18 in the dispatcher's office 20 are in the positions corresponding to the first condition, train control rails 11 and 12 are energized with positive direct current and alternating current.

When polarized relay 15 is negatively energized 25 alternating current relay 16 is energized with alternating current corresponding to the second condition, armatures 80, 81 and 82 of relay 15 will make contact with front contacts 83, 84 and 85, but polarized armatures 86, 87 and 88 are now in the left hand position, opposite to 30 that shown in Fig. 1 and will make contact with contacts 104, 105 and 106. Armatures 92 and 93 of relay 16 will still be in the energized position and armature 92 will make contact with front 35 contact 94. This position of the several armatures establishes a branch circuit from terminal 40 in the main dispatcher's circuit to train control rails 11 and 12 as follows: From terminal 40, wire 95, armature 92, front contact 94, wire 96, 40 armature 80, front contact 83, wire 97, armature 86, contact 104, wire 107, and wires 108, 102 and 103 to train control rails 11 and 12. Under these conditions the train control rails are charged with negative direct current and alternating current.

When polarized relay 15 is positively energized 45 and alternating current relay 16 is deenergized, corresponding to the third condition, armatures 80, 81 and 82 of relay 15 will make contact with front contacts 83 and 84 and 85 and polarized armatures 86, 87 and 88 will make contact with contacts 89, 90 and 91. Armatures 92 and 93 of relay 16 will be in the deenergized position and make contact with the back contacts 109 50 and 110. This position of the several armatures establishes a branch circuit from terminal 40 in the dispatcher's circuit to train control rail 11 and 12 as follows: From terminal 40, wire 95, armature 92, back contact 109, wire 111, armature 81, front contact 84, and wires 112, 108, 102 and 103 to train control rails 11 and 12. Under these conditions train control rails 11 and 12 are charged with positive direct current, only.

When polarized relay 15 is negatively energized 55 and alternating current relay is deenergized, corresponding to the fourth condition, armatures 80, 81 and 82 of relay 15 make contact with front contact 83, 84 and 85, but polarized armatures 86, 87 and 88 are now in the left hand position and make contact with front contacts 104, 105 and 106. Armatures 92 and 93 of relay 16 60 are now in the deenergized position and make contact with back contacts 109 and 110. This position of the several armatures establishes a 70 branch circuit from terminal 40 in the main

dispatcher's circuit to train control rails 11 and 12 as follows: From terminal 40, wire 95, armature 92, back contact 109, wire 111, armature 81, front contact 84, and wires 112, 108 and 102 and 103 to train control rails 11 and 12. Under 5 these conditions train control rails 11 and 12 are energized with negative direct current, only.

When polarized relay 15 is deenergized and alternating current relay 16 is energized corresponding to the fifth condition, armatures 80, 81 and 82 of relay 15 are in the deenergized position and armature 80 will make contact with back contact 113. Armatures 92 and 93 of relay 16 will be in the energized position and armature 92 will make contact with front contact 94. This 15 position of the several armatures establishes a branch circuit from terminal 40 in the main dispatcher's circuit to train control rails 11 and 12 as follows: From terminal 40, wire 95, armature 92, front contact 94, wire 96, armature 80, 20 back contact 113, and wires 112, 108, 102 and 103 to train control rails 11 and 12. Under these conditions train control rails 11 and 12 are charged with alternating current, only.

When polarized relay 15 and alternating current relay 16 are both deenergized, corresponding to the sixth condition, train control rails 11 and 12 are also deenergized, since switches 17 and 18 in the dispatcher's office are open.

Polarized armatures 87 and 88 are pole changing members of a switch for the purpose of changing the direction of flow of current through motor 114, of switch machine 9 the operation of which will be described hereinafter.

It will thus be seen that the dispatcher may 35 electrically condition train control rails 11 and 12 to any one of the six hereinbefore described conditions. The system is so arranged however, that the first condition, that is when the train control rails are charged with positive direct current and alternating current, is also subject to the control of a track circuit. Thus when the dispatcher has placed the switches 17 and 18 to correspond to the first condition and there is a train in block B, track relay 5b will become deenergized in a manner well known to those skilled in the art and armature 100 will drop and break front contact 99. When this occurs no energy can reach train control rails 11 and 12 and therefore they become deenergized, resulting in the 40 sixth condition. It is further obvious to those skilled in the art, that when track switch 7 is open, but there is no train in block B, track relay 5b may also be deenergized in the usual manner and thus establish the sixth condition in the train control rails.

Since only the branch circuit resulting from the first condition, is taken through the armature of track relay 5b, electrical conditions, as second, third, fourth, and fifth are independent of such track circuit control and the train control rails 11 and 12 will be charged as intended by the dispatcher, whether there is a train in block B or not. It will be obvious, however, to those skilled in the art, that any one of the other branch circuits corresponding to any of the other electrical conditions, may be taken through track relay 5b in a similar manner, thus making the circuit, representing any particular conditions, also subject to track circuit control.

The branch circuits through which train control rails 13 and 14 are energized are similar to the circuits controlling train control rails 11 and 12. The only difference is that the branch circuit resulting from the second condition is taken

40

50

55

60

65

70

75

through track relay 5c instead of the first condition branch circuit, for a purpose to be more fully explained hereinafter.

When polarized relay 115 is positively energized and alternating current relay 116 is energized with alternating current, corresponding to the first condition, armatures 117, 118 and 119 of relay 115 will make contact with front contacts 120, 121 and 122 and polarized armatures 126, 127 and 128 are in the right hand position and make contact with contacts 129, 130 and 131. Armatures 132 and 133 of relay 116 will be in the energized position and armature 132 will make contact with front contact 134. This position of the several armatures establishes a circuit from terminal 54 in the main dispatcher's circuit to train control rails 13 and 14 as follows: From terminal 54, wire 135, armature 132, front contact 129, wires 138, 139, 140 and 141, to train control rails 13 and 14. It will be noted that this branch circuit is not taken through track relay 5c.

When polarized relay 115 is negatively energized and alternating current relay 116 is energized with alternating current, corresponding to the second condition, armatures 117, 118 and 119 make contact with front contacts 120, 121 and 122 and the polarized armatures are in the left hand position making contact with contacts 142, 143 and 144. Armatures 132 and 133 of relay 116 will be in the energized position and armature 132 will make contact with contact 134. This position of the several armatures establishes a branch circuit as follows: From terminal 54, wire 135, armature 132, front contact 134, wire 136, armature 117, front contact 120, wire 137, armature 126, contact 142, wire 145, front contact 146, armature 147, of track relay 5c, and wires 148, 149 and 141 to train control rails 13 and 14. It will be noted that this branch circuit is taken through the armature of track relay 5c.

When polarized relay 115 is positively energized and alternating current relay 116 is de-energized corresponding to the third condition, armatures 117 and 118 and 119 will make contact with front contacts 120, 121 and 122 and the polarized armatures will be in the right hand position and make contact with contacts 129, 130 and 131. Armatures 132 and 133 of relay 116 will be in the deenergized position and will make contact with back contacts 149 and 150. This position of the several armatures establishes a branch circuit as follows: From terminal 54, wire 135, armature 132, back contact 149, wire 151, armature 118, front contact 121, and wires 152, 139, 140 and 141 to train control rails 13 and 14.

When polarized relay 115 is negatively energized and the alternating current relay is de-energized, corresponding to the fourth condition, armatures 117, 118 and 119 will make contact with front contacts 120, 121 and 122 and polarized armatures will be in the left hand position making contact with contacts 142, 143 and 144. Armatures 132 and 133 will make contact with back contacts 149 and 150. This position of the several armatures establishes a branch circuit as follows: From terminal 54, wire 135, armature 132, back contact 149, wire 151, armature 118, front contact 121, wires 152, 139, 140, 141 to train control rails 13 and 14.

When polarized relay 115 is deenergized and alternating current relay 116 is energized, corresponding to the fifth condition, armatures 117, 118 and 119 assume the deenergized position and armature 117 will make contact with back con-

tact 153. Armatures 132 and 133 assume the energized position and armature 132 makes contact with front contact 134. This position of the armatures will establish a branch circuit as follows: From terminal 54, wire 135, armature 132, front contact 134, wire 136, armature 117, back contact 153, and wires 152, 139, 140 and 141 to train control rails 13 and 14.

When polarized relay 115 and alternating current relay 116 are both deenergized, corresponding to the sixth condition, train control rails 13 and 14 are deenergized since switches 17 and 18 in the dispatcher's office are open.

Polarized armatures 127 and 128 are pole changing members of a switch for the purpose of changing the direction of the flow of current through motor 154 of switch machine 10, the operation of which will be described hereinafter.

It will thus be seen that the dispatcher may electrically condition train control rails 13 and 14 similar to train control rails 11 and 12, but the branch circuit established under the second condition is taken through track relay 5c, so that when there is a train in block C, train control rails 13 and 14 will be deenergized corresponding to the sixth condition.

While I have provided polarized relay 15 and an alternating current relay 16 at track switch 7 and a similar polarized relay 115 and alternating current relay 116 at track switch 8 which control branch circuits to train control rails 11 and 12 and 13 and 14 respectively, it will be obvious to those skilled in the art that one polarized relay as 15 and one alternating current relay as 16 could properly control the branch circuits to both sets of train control rails 11 and 12 and 13 and 14. Where a siding is long, it is preferred to provide two sets of relays as shown in Fig. 1 since the cost of the wires of the branch circuits would be greater than to provide two additional relays, but where a siding is short, it may be more economical to provide wires needed for the several branch circuits to train control rails 11 and 12 and 13 and 14 from one set of relays.

I will now describe the apparatus and circuits on the locomotive or car. There are six instrumentalities and circuits on the locomotive or car designated as No. 1, No. 2, No. 3, No. 4, No. 5, and No. 6, as shown in Fig. 2. While these instrumentalities are shown as lamps, they may equally as well represent an electromagnetic device to which motion is given depending upon whether the circuit is energized or deenergized. Such electromagnetic devices may be used for other purposes than, or in addition to, the display of signals to the engineer, such as is well known in the art, for example the proper control of speed control devices, or electropneumatic air valves, or both.

In Fig. 2 is shown a four-pole double-throw switch designated as S. When the locomotive is traveling eastward over the division, switch S is in the right hand position as shown in Fig. 2 and when a locomotive is traveling westward over a division, switch S is in the left hand position opposite to that shown in Fig. 2. The object of this switch is to transpose circuits to signals No. 1, No. 2, No. 3 and No. 4, depending upon whether a locomotive is traveling eastward or westward and is for the purpose of directional control, similar to my pending application Serial No. 631,096, filed April 10, 1923 and which is now U. S. Reissue Letters Patent 17,395.

By reason of switch S being in the right hand position for an east bound locomotive and in the

left hand position on a west bound locomotive, when a locomotive is passing a train control rail, which is energized with positive direct current and alternating current, signal No. 1 will be displayed on an east bound locomotive, but signal No. 2 will be displayed on a west bound locomotive. When a locomotive is passing a train control rail which is energized with negative direct current and alternating current, signal No. 1 will be displayed on a west bound locomotive but signal No. 2 will be displayed on an east bound locomotive. When a locomotive is passing a train control rail which is energized with positive direct current only, signal No. 3 will be displayed on an east bound locomotive but signal No. 4 will be displayed on a west bound locomotive. When a locomotive is passing a train control rail which is energized with negative direct current only, signal No. 3 will be displayed on a west bound locomotive and signal No. 4 will be displayed on an east bound locomotive. Since the positions of switch S only transposes the circuits of signals Nos. 1, 2, 3 and 4, signals Nos. 5 and 6 are not affected by the position of switch S, and therefore when a locomotive is passing a train control rail which is energized with alternating current, signal No. 5 will be displayed on both an east bound and a west bound locomotive and when a locomotive is passing a train control rail which is deenergized, signal No. 6 will be displayed on both an east bound and a west bound locomotive.

The cab apparatus and circuits capable of displaying six different signals, corresponding to the six different electrical conditions of the train control rails as hereinbefore enumerated, are shown in Fig. 2 and are similar to the apparatus and circuits shown in my prior Patent No. 1,399,027, granted December 26, 1921, except that the four-pole double-throw switch has been added.

In Fig. 2 is shown an electrical contact shoe as 155 so positioned on the locomotive as to make contact with train control rail 11. The contact shoe is hinged at 156. The train control rails are inclined at the ends so as to form a ramp in the usual manner, such as is shown in my prior Patent No. 1,140,623, granted May 24, 1915. When the contact shoe slides along the ramp, the shoe is tilted so as to break contacts 157, 158 and 159. This motion of the shoe compresses a spring as 160. When the contact shoe leaves the other end of a train control rail, spring 160 forces the contact shoe to the normal position, thus again closing contacts 157, 158 and 159. A metallic plate as 161 fixed to contact shoe 155, but insulated therefrom, is so positioned as to make contact with contacts 158 and 159. The locomotive also carries a polarized relay as 162 and an alternating current relay as 163 with its companion direct current winding as 164, a battery as 165, and another battery as 166. Polarized relay 162 controls the position of neutral armatures as 167, 168 and 169 and polarized armatures as 170, 171, 172 and 173. Alternating current relay 163 and its companion direct current winding 164 control the position of the armatures 174 and 175. Polarized armatures 172 and 173 are pole changing members of a switch for the purpose of changing the flow of current from battery 165. An impedance coil as 176 is inserted in the circuit through polarized relay 162 to prevent the flow of alternating current through the circuit 75 and a condenser 177 is inserted in the circuit

through alternating current relay 163 to prevent the flow of direct current through the circuit.

Armature 167 of relay 162 controls a stick circuit through relay 162 which will be described hereinafter and armature 174 of relay 163 controls a second stick circuit through coil 164 which will be also described hereinafter. A four-pole double-throw switch S consists of four pole members 178, 179, 180 and 181, hinged respectively at 182, 183, 184 and 185. The other ends of these pole members are connected by an insulating bar as 186 to which is attached a handle as 187. In the right hand position of switch S as shown in Fig. 2, normal for an east bound movement, pole members 178, 179, 180 and 181 make contact with terminals 188, 189, 190 and 191 respectively. When switch S is in the left hand position, opposite to that shown in Fig. 2 and normal for a west bound train, pole members 178, 179, 180 and 181 make contact with terminals 192, 193, 194 and 195 respectively. Terminals 188 and 193 are connected by wire 196. Terminals 189 and 192 are connected by a wire 197. Terminals 190 and 195 are connected by wire 198 and terminals 191 and 194 are connected by wire 199.

I will now describe the operation of the six different signals on the locomotive in response to the six different electrical conditions of the train control rails as hereinbefore described.

First condition.—When switch S is in the right hand position, normal for an east bound train movement, and the locomotive is passing a train control rail which is energized with positive direct current and alternating current direct current will flow from train control rail 11, contact shoe 155, wires 200, and 201, impedance coil 176, wire 202, polarized relay 162, wires 203, 204, 205 and 206, axle 207, wheel 208, to track rail 1 and thence the circuit is completed through the positive direct current circuit. This will result in armatures 167, 168, and 169 of relay 162 making contacts with front contacts 209, 210, 211 and polarized armatures 170, 171, 172 and 173 will make contact with their respective contacts 212, 213, 214 and 215. Alternating current will also flow from train control rail 11, shoe 155, wires 200 and 216, condenser 177, wire 217, alternating current relay 163, wire 218, and wires 204, 205 and 206, axle 207, wheel 208 to track rail 1 and thence the circuit is completed through the alternating current circuit as hereinbefore described. This will result in armatures 174 and 175 of relay 163 making contact with front contacts 219 and 220. In this position of the armatures a circuit is established through signal No. 1 as follows: From positive pole of battery 165, wires 221 and 222, contact 214, armature 172, wire 223, armature 175, front contact 220, wire 224, armature 168, front contact 210, wire 225, polarized armature 170, contact 212, wire 226, hinge 182, pole member 178, contact 188, wire 227, signal No. 1, wires 228, 205, and 229, polarized armature 173, contact 215, wire 230, to negative pole of battery 165.

When the contact shoe leaves the other end of the train control rail, the armatures of relays 162 and 163 are maintained in the same position after the electro-motive forces from the dispatcher's office cease to influence them through the two following stick circuits: As the contact shoe is leaving the train control rail, spring 160 closes contacts 157, 158 and 159 and a stick circuit is established through relay 162 as follows: From positive pole of battery 165, wires 221 and 222, contact 214, polarized armature 172, wire 231, armature 167, front contact 209, wire 232, con-

tact 157, shoe 155, wires 200 and 201, impedance coil 176, wire 202, polarized relay 162, wires 203, 204 and 229, polarized armature 173, contact 215, and wire 230 to the negative pole of battery 165.

5 This stick circuit will be referred to hereafter as the positive polarized relay stick circuit.

A second stick circuit is established through coil 164 of relay 163 as follows: From battery 166, wire 233, coil 164, wire 234, contact 159, metallic 10 contact plate 161, contact 158, wire 235, front contact 219, armature 174, and wire 236 to the other side of battery 166. This stick circuit will be referred to hereinafter as the alternating current relay stick circuit.

15 It will thus be seen that by reason of the two stick circuits just described, the armatures of relays 162 and 163 are maintained in the same position, thus continuing the display of signal No. 1 until the next train control rail is reached.

20 Still speaking of the first condition of the train control rail that is, when it is energized with positive direct current and alternating current, but assuming that switch S is in the left hand position, normal for a west bound train. Under these 25 conditions polarized relay 162 will be positively energized and alternating current relay 163 will be energized, thus leaving the armatures of the two relays in the same position as heretofore described, but by reason of switch S being in the 30 left hand position, a circuit through signal No. 2 is established instead of through signal No. 1 as follows: From positive pole of battery 165, wire 221, and 222, contact 214, polarized armature 172, wire 223, armature 175, front contact 220, wire 35 224, armature 168, front contact 210, wire 225, polarized armature 170, contact 212, wire 226, hinge 182, pole member 178, terminal 192, wire 197, terminal 189, wire 237, signal No. 2 and wires 228, 205 and 229, polarized armature 173, contact 40 215, and wire 230, to negative pole of battery 165.

When the contact shoe leaves the other end of the train control rail the positions of the armatures of relay 162 and 163 are maintained in the 45 same positions, since the two stick circuits, the positive polarized relay stick circuit and the alternating current relay stick circuit are still effective. Thus signal No. 2 will be continued.

Second condition.—When switch S is in the 50 right hand position, and the locomotive is passing a train control rail which is energized with negative direct current and alternating current, polarized relay 163 will be negatively energized through a circuit as follows: From track rail 1, 55 wheel 208, axle 207, wires 206, 205, 204 and 203, polarized relay 162, wire 202, impedance coil 176, wires 201 and 200, contact shoe 155, to train control rail 11 and thence the circuit is completed through the negative direct current circuit as 60 hereinbefore described. Alternating current relay 163 will also be energized through a circuit hereinbefore described. Armatures 167, 168 and 169 of relay 162 will still be in the energized position but polarized armatures 170, 171, 172 and 173 65 will make contact with contacts 238, 239, 240 and 241. In this position of the several armatures a circuit is established through signal No. 2 as follows: Positive pole of battery 165, wires 221 and 242, contact 241, polarized armatures 173, wires 229, 205 and 228, signal No. 2, wire 237, terminal 189, pole member 179, hinge 183, wire 243, contact 238, polarized armature 170, wire 225, front contact 210, armature 168, wire 224, front contact 70 220, armature 175, wire 223, polarized armature

172, contact 240, and wire 230 to negative pole of battery 165.

When the contact shoe leaves the other end of train control rail a stick circuit is established through relay 162 as follows: From positive pole 5 of battery 165, wires 221 and 242, contact 241, polarized armature 173, wires 229, 204 and 203, polarized relay 162, wire 202, impedance coil 176, wire 201 and 200, contact shoe 155, contact 157, wire 232, front contact 209, armature 167, wire 231, polarized armature 172, contact 240, and wire 230, to negative pole of battery 165. This particular stick circuit will be referred to hereinafter as the negative polarized relay stick circuit. Alternating current relay 163 is still energized 15 and the alternating relay stick circuit is effective. Thus signal No. 2 will be continued.

Still speaking of the second condition of the train control rail, but assuming that switch S is in the left hand position, then a circuit will be 20 established through signal No. 1 as follows: From positive pole of battery 165, wires 221 and 242, contact 241, polarized armature 173, wires 229, 205 and 228, signal No. 1, wire 227, terminal 188, wires 196, terminal 193, pole member 179, hinge 25 183, wire 243, contact 238, polarized armature 170, wire 225, front contact 210, armature 168, wire 224, front contact 220, armature 175, wire 223, armature 172, contact 240, and wire 230 to the negative pole of battery 165.

As the contact shoe leaves the other end of the train control rail the negative polarized relay stick circuit and the alternating current relay stick circuit are both effective and signal No. 1 30 is continued.

Third condition.—When switch S is in the right hand position and the locomotive is passing a train control rail which is energized with positive direct current only, polarized relay 162 will be 40 positively energized and the position of its armatures will be the same as hereinbefore described under the first condition. Alternating current relay 163 however will be deenergized since its stick circuit is now open at front contact 157. Armatures 174 and 175 will assume the deenergized position and armature 175 will make contact with back contact 244. In this position of the several armatures a circuit is closed through signal No. 3 as follows: Positive pole of battery 165, wires 221 and 222, contact 214, armature 172, wire 223, armature 175, back contact 244, wire 245, armature 169, front contact 211, wire 246, armature 171, contact 213, wire 247, hinge 184, pole member 180, terminal 190, wire 248, signal No. 3, wires 228, 205 and 229, armature 173, contacts 215, 55 wire 230 to negative pole of battery 165.

As the contact shoe leaves the other end of a train control rail, the positive polarized relay stick circuit is effective but the alternating current relay stick circuit is inoperative since the 60 front contact 219 is now open. Thus signal No. 3 is continued.

Still speaking of the third condition of the train control rails, but assuming that switch S is in the left hand position, polarized relay 162 is positively energized and relay 163 is deenergized and a circuit is closed through signal No. 4 as follows: Positive pole of battery 165, wires 221, and 222, contact 214, polarized armature 172, wire 223, armature 175, back contact 244, wire 245, armature 169, front contact 211, wire 246, armature 171, contact 213, wire 247, hinge 184, pole member 180, terminal 194, wire 199, terminal 191, wire 249, signal No. 4, wires 228, 205 and 229, 70 75

armature 173, contact 215 and wire 230 to the negative pole of battery 165.

As the contact shoe leaves the other end of the train control rail the positive polarized relay stick circuit is again effective but the alternating current relay stick circuit is inoperative. Thus signal No. 4 is continued.

Fourth condition.—When switch S is in the right hand position and a locomotive is passing a train control rail, which is energized with negative direct current only, polarized relay 162 is negatively energized and alternating current relay 163 is deenergized. Polarized armature 170, 171, 172 and 173 will be in the left hand position and make contact with contacts 238, 239, 240 and 241. This position of the several armatures will close a circuit through signal No. 4 as follows: Positive pole of battery 165, wires 221 and 242, contact 241, polarized armature 173, wires 229, 205 and 228, signal No. 4, wire 249, terminal 191, switch member 181, hinge 185, wire 250, contact 239, armature 171, wire 246, front contact 211, armature 169, wire 245, back contact 244, armature 175, wire 223, armature 172, contact 240 and wire 230 to the negative pole of battery 165.

As the contact shoe leaves the other end of the train control rail the negative polarized relay stick circuit is effective but the alternating current relay stick circuit is inoperative. Thus signal No. 4 is continued.

Still speaking of the fourth condition of the train control rails but assuming that switch S is in the left hand position, polarized relay 162 is negatively energized and alternating current relay 163 is deenergized and the circuit is closed through signal No. 3 as follows: Positive pole of battery 165, wires 221 and 242, contact 241, armature 173, wires 229, 205 and 228, signal No. 3, wire 248, terminal 190, wire 198, terminal 195, pole member 181, hinge 185, wire 250, contact 239, armature 171, wire 246, front contact 211, armature 169, wire 245, back contact 244, armature 175, wire 223, armature 172, contact 240, and wire 230, to the negative pole of battery 165.

As the contact shoe leaves the other end of the train control rail, the negative polarized relay stick circuit is effective but the alternating current relay stick circuit is inoperative, thus signal No. 3 is continued.

Fifth condition.—Irrespective of whether switch S is in the left hand position and the locomotive is passing a train control rail which is energized with alternating current, polarized relay 162, will become deenergized and its neutral armatures 167, 168 and 169 will assume the deenergized position. Armatures 168 and 169 will close back contacts 251 and 252 and alternating current relay 163 will be energized and armature 174 and 175 will close front contacts 219 and 220. This position of the several armatures closes a circuit through signal No. 5 as follows: From positive pole of battery 165, wires 221 and 222, contact 214, armature 172, wire 223, armature 175, front contact 220, wire 224, armature 168, contact 251, wire 253, signal No. 5, and wires 228, 205 and 229, armature 173, contact 215, and wire 230 to the negative pole of battery 165. The negative polarized relay stick circuit is now inoperative since the front contact 209 is now open but the alternating current relay stick circuit is effective, thus signal No. 5 is continued.

Sixth condition.—Irrespective of whether switch S is in the right hand position or left hand position, and a train passes a train control rail which is deenergized the two stick circuits

will be open at contacts 157, 158 and 159 and both relays 162 and 163 will become deenergized. Armatures 167, 168 and 169 will assume the deenergized position and armature 175 will close back contact 244. This position of the several armatures will close a circuit through signal No. 6 as follows: From positive pole of battery 165, wires 221 and 222, contact 214, armature 172, wire 223, armature 175, back contact 244, wire 245, armature 169, back contact 252, wire 254, signal No. 6, wires 228, 205 and 229, armature 173, contact 215, and wire 230 to the negative pole of battery 165.

As the contact shoe leaves the other end of the train control rail both stick circuits are now inoperative since both front contacts 209 and 219 are open, thus signal No. 6 will be continued, until an energized train control rail is encountered.

It must be understood that each time a contact shoe 155 slides onto a train control rail, both stick circuits are opened at contacts 151, 158 and 159 and therefore both relays 162 and 163 would become deenergized resulting in a display of signal No. 6 unless energy of some character is furnished from the dispatcher's office while contact shoe 155 is in contact with a train control rail.

I will now describe the indicating or recording apparatus in the dispatcher's office. A record sheet as 255 is suitably mounted and driven by a roller as 256, which in turn is driven by a shaft 251. Shaft 251 receives motion through a ratchet wheel as 258. A pawl as 259 is pivotally mounted on armature 260 of electro magnet 261. Armature 260 is hinged at 262. When electro magnet 261 is periodically energized, motion is given to ratchet wheel as 258 through pawl 259. A spring as 263 normally pulls armature 260 and pawl 259 to the right, when electro magnet 261 is not energized. Electro magnet 261 is connected by wire 264 to a make-and-break device as 265 which make-and-break device is periodically operated by a clock as 266. This may well be of the form as shown in my prior Patent No. 1,203,146 granted October 21, 1916. When the make-and-break device 265 is closed, the electro magnet 261 is energized through the following circuit: Battery 267, wire 268, electro magnet 261, wire 264, make-and-break device 265, wire 269, to the other side of battery 267. The make-and-break device 265 is operated say every five seconds by the clock 266 so as to give a slow and uniform motion to record sheet 255, through ratchet wheel 258 and pawl 259. The record sheet is transversely divided into sections 270, each section corresponding to a double ended siding. Longitudinally the record sheet is divided into time lines such as 1.00 A. M. each one of the lines representing a one minute interval. Since the make-and-break device is operated intermittently continuously it will be seen that longitudinally it assumes a constantly changing position during the 24 hours of the day.

Adjacent to the record sheet are perforating magnets as 271, 272 and 273; perforating magnet 271 responding to the positive direct current circuit, perforating magnet 272 responding to the negative direct current circuit and perforating magnet 273 responding to the alternating current circuit. Pivotaly attached to armatures 274 of these perforating magnets are perforating needles as 275, so positioned adjacent to the record sheet that when a perforating magnet is energized, a perforation is made on the record sheet. Attached to switches 17 and 18 are me-

- tallic wedges as 276 which are, however, insulated from the switches 17 and 18. When the switch 17 is in contact with spring contact 19, metallic wedge 276 will electrically connect spring contacts 271 and 278. When switch 17 makes contact with contact spring 20, metallic wedge 276 will electrically connect contact spring 279 and 280 and when switch 18 is in contact with spring contact 21, metallic wedge 276 will electrically connect spring contacts 281 and 282. The circuits through the perforating magnets 271 and 272 are controlled by relay 29 and the circuit through perforating magnet 273 is controlled by alternating current relay 30.
- 15 When switch 17 is in contact with spring contact 19 and there is no train in block A or block D, current is flowing through relay 29, but this current is not sufficient by reason of resistance 36 and 50 in the main circuit to attract armature 283 and close front contact 284, and therefore the circuit through perforating magnet 271 is not closed. If, however, there is a train in block A, track relay 5a becomes deenergized and armature 285 of track relay 5a closes back contact 286 and establishes a shunt circuit which cuts out resistances 36 and 50 as follows: From terminal 34 in the main dispatcher's office, wire 287, armature 285 of track relay 5a, back contact 286, wire 288, to track rail 1, and thence the circuit is completed through the positive direct current circuit heretofore described. With resistance 36 and 50 thus cut out of the circuit, there is then sufficient current flowing through relay 29 to attract armature 283 and close front contact 284. When this occurs a circuit is closed through perforating magnet 271 as follows: From battery 267, wire 289, metallic contact plate 290, bus 291, wire 292, perforating magnet 271, wire 293, contact spring 277, metallic wedge 276, contact spring 278, wire 294, front contact 284, armature 283, wire 295, and bus 296, to the other side of battery 267. Similarly when block D is occupied, armature 287 of track relay 5d will close back contact 298, and a similar shunt circuit is established from terminal 34 in the main dispatcher's circuit, wire 47, terminal 48, wire 299, armature 297, of track relay 5d, back contact 298, wire 300, to track rail 1 and thence the circuit is completed through the positive direct current circuit as hereinbefore described. When this shunt circuit is established there is again sufficient current flowing through relay 29 for armature 283 to close front contact 284 and close the circuit through perforating magnet 271.
- 55 When switch 17 is in contact with spring contact 20 the circuit through perforating magnet 272 is closed at contact springs 279 and 280 through metallic wedge 276. As long however, as there is no train on blocks A or D, there is not sufficient current flowing through relay 29 to attract armature 283 and close contact 284, but as soon as the shunt circuit through armature 285 of track relay 5a or armature 297 of track relay 5d, is closed as hereinbefore described, there is sufficient current flowing through relay 29 to attract armature 283 and close front contact 284, and then the circuit is closed through perforating magnet 272 as follows: From battery 267, wire 289, metallic contact plate 290, metallic wedge 276, contact spring 280, wires 303 and 294, front contact 284, armature 283, wire 295, and bus 296 to the other side of battery 267.
- 70 When switch 18 is in contact with spring contact 21 the circuit through perforating magnet 273 is closed at contact springs 281 and 282,

through metallic wedge 276. As long, however, as there is no train in blocks A or D, there is not sufficient current flowing through relay 30 to attract armature 304 and close front contact 305, but as soon as the shunt circuit through armature 285 of track relay 5a or armature 297 of track relay 5d is closed, as hereinbefore described, there is sufficient current flowing through relay 30 to attract armature 304 and close front contact 305 and then the circuit is closed through perforating magnet 273 as follows: From battery 267, wire 289, metallic plate 290, bus 291, wire 306, perforating magnet 273, wire 307, contact spring 281, metallic wedge 276, contact spring 282, and wire 308, front contact 305, armature 304, bus 296, to the other side of battery 267.

It will thus be seen that when either one of the switches 17 or 18 makes contact with spring contacts 19 or 20 or 21 and a train enters either block A or D the respective perforating magnet 271, 272 or 273 is energized and makes a perforation in the record sheet 255, thus giving the exact time when a train entered block A or D. It will be noted that the circuits through perforating magnets 271, 272 and 273 are taken through metallic plate 290, which is a circuit breaking device through which the circuits are periodically made and broken. This circuit breaking device operates as follows: metallic contact plate 290, is attached to armature 260 and insulated therefrom. Every time the electro magnet 261 is energized, which as hereinbefore stated is say every five seconds, the circuits through wires 289 and bus 291 are closed through metallic plate 290. When magnet 261 is deenergized armature 260 is pulled to the right by spring contact 263 and the circuit through wire 289 and bus 291 is broken. By reason of this periodic breaking of the circuit through perforating magnets 271, 272 and 273, an intermittently continuous perforation is made on the record sheet as long as blocks A or D are occupied, and the record will show the exact time a train entered blocks A or D and the length of time the train remained in the block. The record will further show, which one of the six electrical conditions of the train control rails had been set up by the dispatcher when a train entered blocks A or D. For instance, if perforating magnet 271 and 273 simultaneously made a record, the first condition was set up. If perforating magnets 272 and 273 made a record simultaneously, the second condition was set up. If perforating magnet 271 alone made a record, the third condition was set up. If perforating magnet 272 alone made a record, the fourth condition was set up. If perforating magnet alone made a record the fifth condition was set up, and if no record is made when a train entered block A or D, it is evident that the sixth condition was set up.

I will now describe the operation of power switch machines 9 and 10. When the dispatcher places switch 17 so as to contact with spring contact 19 and opens switch 18 and disconnects it from spring contact 21, that is when the third condition is set up in the train control rails, polarized relay 15 near track switch 7 is positively energized and alternating current relay 16 near track switch 7 is deenergized. Under these conditions a circuit is closed through motor 114 of switch machine 9 as follows: From positive pole of battery 309, wire 310, contact 91, polarized armature 88, of relay 15, wire 311, front contact 85, armature 82, wire 312, back contact 110, armature 93 of relay 16, wire 313, armature 314, of track relay 5a, front contact 315, wire 316,

motor 114, of switch machine 9, wires 317 and 318, polarized armature 87 of relay 15, contact 90, wires 319, and 320, to negative pole of battery 309. When this circuit is completed, current is flowing through motor 114 of switch machine 9 and the connections to the motor are so arranged that track switch 7 will be closed.

Similarly when the dispatcher's switches are set up for the third condition, polarized relay 115 near track switch 8 is positively energized and alternating current relay 116 near track switch 8 is deenergized, and a circuit is closed through motor 154 of switch machine 10 as follows: From positive pole of battery 321, wire 322, contact 131, polarized armature 128 of relay 115, wire 223, front contact 122, armature 119 of relay 115, wire 224, back contact 150, armature 133, of relay 116, wire 325, armature 326, of track relay 5d, front contact 327, wire 328, motor 154 of switch machine 10, wires 329 and 330, polarized armature 127 of relay 115, contact 130, wires 331 and 332, to negative pole of battery 321. When this circuit is completed, current is flowing through motor 154 of switch machine 10 and the connections to the motor are so arranged that track switch 8 will be open.

When the dispatcher places switch 17 so as to contact with spring contact 20 and opens switch 18 and disconnects it from spring contact 21, that is when the fourth condition is set up in the train control rails, polarized relay 15 near track switch 7 is negatively energized and alternating current relay 16 near track switch 7s is deenergized. Under these conditions, polarized armatures 87 and 88 of relay 15 are in the left hand position, opposite to that shown in Fig. 1, and the circuit through motor 114 of switch machine 9 is again closed, except that the current is now flowing in the opposite direction, as follows: From positive pole of battery 309, wire 310, contact 105, polarized armature 87, wires 318 and 317, motor 114, wire 316, contact 315, armature 314, wire 313, armature 93, back contact 110, wire 312, armature 82, front contact 85, wire 311, polarized armature 88, contact 106, and wires 333 and 320 to negative pole of battery 309. When current is flowing through motor 114 in this direction switch machine 9 will place track switch 7 in the open position.

Similarly when the dispatcher's switches are set up for the fourth condition, polarized relay 115 will be negatively energized and alternating current relay 116 will be deenergized. Under these conditions polarized armatures 127 and 128 of relay 115 are in the left hand position opposite to that shown in Fig. 1, and the circuit through motor 154 of switch machine 10 is again closed except that the current is now flowing in the opposite direction as follows: From positive pole of battery 321, wire 322, contact 143, polarized armature 127, wires 330, and 329, motor 154, wire 328, front contact 327, armature 326, wire 325, armature 133, back contact 150, wire 224, armature 119, front contact 122, wire 223, polarized armature 128, contact 144, and wires 334 and 332, to the negative pole of battery 321. When current is flowing through motor 154 in this direction, switch machine 10 will place track switch 8 in the closed position.

It will be noted that the circuit through motor 114 of switch machine 9 is taken through armature 314 of track relay 5a and similarly the circuit through motor 154 of switch machine 10 is taken through armature 326 of track relay 5d.

75 This is for the purpose of preventing the dis-

patcher from moving track switch 7 from the position it is in after a train has entered block A and similarly moving track switch 8 from the position it is in after a train has entered block D. As soon as a train enters either block A or block 5 D, their corresponding track relays 5a or 5d become deenergized, in a manner well known to those skilled in the art, and the circuits through motors 114 or 154 are broken, thus preventing any movement in switch machine 9 or 10.

Under some conditions it may be desirable to duplicate some of the signals given on the locomotive, by means of fixed signals along the track. In Fig. 1 is shown such an arrangement whereby a fixed signal near track switch 7 is controlled by a relay as shown at 335, for governing an east bound train and a similar relay as shown at 336 near switch 8 controlling a signal for governing a west bound train. The fixed signals may be light signals or semaphore signals controlled by 15 relays as 335 and 336 in a manner well known to those skilled in the art. When relay 335 or 336 is energized a clear signal is displayed and when deenergized a danger signal is displayed.

The circuit through relay 335 is taken through 25 armature 337 of track relay 5b and is as follows: From positive pole of battery 309, wire 310, contact 91, polarized armature 88, wires 311 and 338, relay 335, wire 339, front contact 340, armature 337 of track relay 5b, wire 318, polarized armature 87, contact 90, and wires 319 and 320 to the negative pole of battery 309. When there is no train in block B, track relay 5b is energized and the circuit through relay 335 is closed and therefore it is in a condition to display a clear signal, 35 but when there is a train in block B, track relay 5b is deenergized, thus breaking the circuit through relay 335, and conditioning it to display a danger signal.

Similarly the circuit through relay 336 is taken 40 through armature 341, of track relay 5c and is as follows: From positive pole of battery 321, wire 322, contact 131, polarized armature 128, wires 223, and 342, relay 336, wire 343, front contact 344, armature 341, of track relay 5c, wires 345 and 330, polarized armature 127, contact 130, and wires 331 and 332 to negative pole of battery 321. When there is no train in block C track relay 5c is energized and the circuit through relay 336 is closed and therefore, the relay is in 45 a condition to display a clear signal but when there is a train in block C, track relay 5c is deenergized, thus breaking the circuit through armature 341 of relay 5c and conditioning relay 336 to display a danger signal.

While I have shown in these specifications and drawings means to control a cab signal by means of a track circuit only, it will be obvious to those skilled in the art that fixed signals could be substituted for cab signals for any one of the six electrical conditions controlled from the dispatcher's office, such, for instance, as are shown in my co-pending application, Serial No. 631,097, filed April 10, 1923 and which is now U. S. Letters Patent 1,604,538, or both cab signals and fixed signals may be used without departing from the spirit of the invention.

The purpose of the invention is first of all to provide instrumentalities or signals to make the operation of trains safe, but in addition also to 70 provide instrumentalities or signals which will enable the dispatcher to facilitate the movement of trains. In the usual form of directing train movements, it is necessary for the dispatcher to telegraph to an operator at a way station to de-

liver a certain order to the train crew. The order may read that the train should proceed to siding 6, stay on the main track and meet another train, or the order may read for the train to proceed 5 to siding 6, pull in on the siding and meet another train. In this latter case, the train proceeds to near the switch at siding 6, and the train must be stopped and a brakeman sent ahead to open the switch so that the train may pull in 10 on the siding. Not only is this operation time consuming but an appreciable amount of coal is wasted, particularly in case of a heavy freight train. With this invention not only is the dispatcher enabled to open the desired switch before 15 the train arrives at the siding, but at the same time he is enabled by means of signals to instruct the engineer that the switch is open and that he should proceed on to the siding at a distance far enough back of the siding switch such 20 as at distant train control rails 12 and 14 to enable him to bring his train from a comparatively high speed at which he may be running to a relatively lower speed near the siding switch so that the train may proceed over the sharp 25 curves of the switch safely.

The signals and instrumentalities described in this invention may be used as follows: When the dispatcher places switches 17 and 18 in the position corresponding to the first condition, signal 30 No. 1 will be displayed on an east bound locomotive, indicating that the track ahead is clear and signal No. 2 will be displayed on a west bound locomotive, indicating to the engineer that the train should stop and that the main track is 35 set up for an east bound movement. When the dispatcher places switches 17 and 18 in the position corresponding to the second condition, signal No. 1 will be displayed on a west bound locomotive indicating that the track ahead is clear 40 and signal No. 2 will be displayed on an east bound locomotive indicating to the engineer that the train should stop and that the main track is set up for a west bound movement.

When the dispatcher places switches 17 and 18 45 in the position to correspond to the third condition, signal No. 3 will be displayed on the east bound locomotive indicating to the engineer that he should stop and meet another train and further that the track switch is closed and that he 50 should stay on the main track, but under these conditions signal No. 4 will be displayed on a west bound locomotive indicating to the engineer that he should stop at the siding and meet another train and further that the track switch is 55 open and that he should pull his train into the siding.

When the dispatcher places switches 17 and 18 60 in the position corresponding to the fourth condition, signal No. 4 will be displayed on an east bound locomotive indicating to the engineer that he should stop and meet another train and further that the track switch is open and that he should pull his train into the siding, but under 65 these conditions signal No. 3 will be displayed on a west bound locomotive indicating to the engineer that he should stop and meet another train at the siding and further that the track switch is closed and that he should remain on the main track.

70 When the dispatcher places switches 17 and 18 75 in the position corresponding to the fifth condition, signal No. 5 will be displayed on both an east bound and a west bound locomotive and may be used to indicate to the engineer to stop and report to the dispatcher and when the dispatcher

places switches 17 and 18 in the position corresponding to the sixth condition signal No. 6 will be displayed on both an east bound and a west bound locomotive, and may be used to indicate to the engineer, to stop, that there is danger 5 ahead. Signal No. 6 will also be displayed irrespective of the placing of the dispatcher's switches if the block ahead is occupied. Or any of the signals may be used for a purpose as designated by the executive officers of the railway. In 10 no case, however, can signal No. 1 or the clear signal be displayed if the block ahead is occupied.

Although I have particularly described and illustrated one preferred physical embodiment of my invention and explained the principle and construction thereof, nevertheless, I desire to have it understood that the form selected is merely illustrative and does not exhaust the possible physical embodiment of means underlying my 15 invention.

What is claimed is:

1. In a railway system, a passing siding section having siding switches adjacent the ends thereof, single track stretches adjacent the ends 20 of said siding section, switch motors for opening and closing said switches, switch motor control means, a signal station governing the entrance of traffic moving in one direction into the passing siding section, a signal station governing the entrance 25 of traffic moving in the other direction into the passing siding section, a dispatcher's office and circuit means therefrom for controlling the switch motor control means and the signal stations 30 for both directions of train operation, means at the dispatcher's office for energizing the circuit means with direct current of either polarity and alternating current, the signal stations being responsive to the presence or absence 35 of alternating current for effecting a proceed indication or a meeting indication, the switch motor control means being responsive to direct current of one polarity or the other for effecting movement of the siding switches to open or closed 40 positions and including means responsive to alternating current for preventing operation of the switch motors, and the signal stations being responsive to the polarity of the direct current. 45

2. In a railway system, a passing siding section having siding switches adjacent the ends thereof, single track stretches adjacent the ends of said siding section, switch motors for opening and closing said switches, switch motor control means, a signal station governing the entrance of traffic moving in one direction into the passing siding section, a signal station governing the entrance of traffic moving in the other direction into the passing siding section, a dispatcher's office and circuit means therefrom for controlling the switch motor control means and the signal stations for both directions of train operation, means at the dispatcher's office for energizing the circuit means with direct current of either polarity and alternating current, the signal stations being responsive to the presence or absence 50 of alternating current for effecting a proceed indication or a meeting indication, the switch motor control means being responsive to direct current of one polarity or the other for effecting movement of the siding switches to open or closed 55 positions and including means responsive to alternating current for preventing operation of the switch motors, the signal stations being responsive to the polarity of the direct current. 60

of a switch motor when a train has approached the switch.

3. In a railway system, a passing siding section having siding switches adjacent the ends thereof, single track stretches adjacent the ends of said siding section, signal means for governing the entrance of trains moving in either direction into the siding section, switch operating means at the trackway for opening and closing said switches, a dispatcher's office and electrical circuit means connecting the office and the signal means and the switch operating means, means at the dispatcher's office for energizing the electrical circuit means with direct current of either polarity and alternating current, the switch operating means being responsive to the polarity of the direct current for either opening or closing the switches and including alternating current responsive means for rendering the switch operating means ineffective, and the signal means being responsive to the polarity of the direct current and responsive to alternating current to establish the signal means for a proceed or a meeting movement.

25 4. In a railway system, a passing siding section having siding switches adjacent the ends thereof, single track stretches adjacent the ends of said siding section, signal means for governing the entrance of trains moving in either direction into the siding section and control means at the trackway for the signal means, switch operating means at the trackway for opening and closing said switches, a dispatcher's office and electrical circuit means connecting the office and the signal control means and the switch operating means, means at the dispatcher's office for energizing the electrical circuit means with direct current of either polarity and alternating current, the switch operating means being responsive to the polarity of the direct current for either opening or closing the switches, the signal control means being responsive to the polarity of the direct current and responsive to the presence or absence of alternating current to establish the signal means for a proceed or a meeting movement, and track relay means for preventing operation of a switch when a train has approached the switch.

5. In a railway system, a passing siding section having siding switches adjacent the ends thereof, single track blocks adjacent the ends of said siding section, signal means for governing the entrance of trains moving in either direction into the passing siding section, switch operating means at the trackway for opening and closing said switches, a dispatcher's office and a line wire extending therefrom to the siding section, said line wire being electrically associated with said switch operating means and the signal means, means at the dispatcher's office for applying direct current of either polarity to the line wire and said switch operating means being responsive to the polarity of the current so applied for normally causing the switches to assume either an open or closed position, means at the dispatcher's office for impressing another electrical condition upon the line wire, and said signal means normally being responsive to said another electrical condition for causing the signal means to indicate a proceed or a meeting movement, and means responsive to said another electrical condition and included in the switch operating means for rendering the latter ineffective to operate the siding switches.

75 6. In a railway system, a passing siding section

having siding switches adjacent the ends thereof, single track blocks adjacent the ends of said siding section, signal means for governing the entrance of trains moving in either direction into the passing siding section, switch operating means at the trackway for opening and closing said switches, a dispatcher's office and a line wire extending therefrom to the siding section, said line wire being electrically associated with said switch operating means and the signal means, means at the dispatcher's office for applying direct current of either polarity to the line wire and said switch operating means being responsive to the polarity of the current so applied for normally causing the switches to assume either an open or closed position, means at the dispatcher's office for impressing another distinctive electrical condition upon the line wire, means responsive to said distinctive electrical condition and associated with the switch operating means for preventing the operation thereof, said signal means normally being responsive to said distinctive electrical condition for causing the signal means to indicate a proceed or a meeting movement, and track circuit means for preventing movement of one switch by the switch operating means when a train approaches said siding section and has entered upon the single track block adjacent said switch.

7. In a train dispatching system, a section of railway track having a passing siding with a track switch, signals for controlling the entrance of trains into said section of track from both directions, a switch machine for operating the track switch, a dispatcher's office, line circuit means from said dispatcher's office extending to the siding section, a direct current responsive relay included in the line circuit means at the siding and located near the switch machine for operating said switch machine, an alternating current responsive relay included in the line circuit means at the siding for disassociating the switch machine from operation by the direct current responsive relay, said signals being associated with the line circuit means and being distinctively responsive to the presence of direct and alternating currents therein, means at the dispatcher's office for independently operating said direct current relay and said alternating current relay through the medium of said line circuit means, and means at said dispatcher's office distinctively detecting the flow of direct and alternating current in said line circuit means.

8. In a train dispatching system, a section of railway track having a passing siding with a track switch at each end thereof, signals associated with said passing siding, switch machine means for operating the track switches, a dispatcher's office, line circuit means from said office extending to the siding section, direct current responsive polar relay means included in the line circuit means at the siding for normally effecting opening or closing of said track switches by the switch machine means in accordance with the polarity of direct current present in the line circuit means, alternating current responsive relay means associated with the line circuit means for controlling said signals and for rendering the switch machine means operable or inoperable by said polar relay means, and means at the dispatcher's office for independently operating said direct current responsive polar relay means and said alternating current responsive relay means through the medium of said line circuit means.

9. In a train dispatching system, a section of

railway track having a passing siding with a track switch at each end thereof, signals associated with said passing siding, switch machine means for operating the track switches, a dispatcher's office, line circuit means extending from said office to the siding section, direct current responsive polar relay means associated with the line circuit means for normally effecting opening or closing of said track switches by the switch machine means and for causing distinctive indications by said signals in accordance with the polarity of the direct current present in the line circuit means, alternating current responsive relay means associated with the line circuit, means for causing said signals to indicate proceed or a meeting and for preventing operation of the switch means by said polar relay means, means at the dispatcher's office for independently operating said direct current responsive polar relay means and said alternating current responsive relay means through the medium of said line circuit means, and means at the dispatcher's office dis-

tinctively detecting the flow of direct and alternating current in said line circuit means.

10. In a train dispatching system, a section of railway tracks having a passing siding with a track switch, signal means for controlling the entrance of trains into said section of track from both directions, a switch machine for operating the track switch, a dispatcher's office and line circuit means extending therefrom to the siding section, means at the siding controlled from the dispatcher's office through the medium of said line circuit means for operating the switch machine, said signal means being associated with the line circuit means, said signal means including means responsive to alternating current in the line circuit means to establish the signal means for proceed or meeting indications and distinctively responsive to the polarity of direct current in the line circuit means, and means at the dispatcher's office for independently applying direct current of either polarity and alternating current to the line circuit means.

PAUL J. SIMMEN.
